UNITED STATES PATENT OFFICE.

FRANK P. HERRGUTH, OF SAN FRANCISCO, CALIFORNIA, ASSIGNOR TO UNIVERSAL WIRELESS TELEPHONE AND TELEGRAPH COMPANY, A CORPORATION OF CALIFORNIA.

TRANSMITTING OF VOCAL AND OTHER SOUNDS.

1,086,530.

Specification of Letters Patent.

Patented Feb. 10, 1914.

Application filed February 19, 1910, Serial No. 544,649. Renewed March 28, 1911. Serial No. 617,496.

To all whom it may concern:

Be it known that I, FRANK P. HERRGUTH, a citizen of the United States, residing at San Francisco, in the county of San Francisco and State of California, have invented certain new and useful Improvements in Transmitting of Vocal and other Sounds, of which the following is a specification.

This invention relates to the transmitting of vocal and other sounds, including articulate speech from one station to another by means of electro-magnetic waves without the use of wires to guide the waves to their destination and has for its object to provide a new and improved system for the above purpose by means of which electro-magnetic waves by the voice, telegraph key or other sounds are transmitted through the air from a transmitter to a receiver which receives the sonorous vibrations sent from the transmitter, said transmitter controlling a rapid intermittent train of the electro-magnetic waves.

Referring to the accompanying drawings, the figure is a diagram of a transmitting system in accordance with this invention in which the amplitude of a rapid intermittent train of electric oscillations may be controlled.

Referring to the figure, the electric current is supplied by means of an electric generator 1, which current may be either a quickly interrupted direct current, or an alternating current. A Wheatstone bridge 2 is located in the same circuit with the generator 1, and in said circuit between the generator 1, and the Wheatstone bridge are located two variable resistances 3. Current is supplied by the generator 1 through the resistances 3, to the four arms of the Wheatstone bridge comprising four induction coils 4, 5, 6, 7. Shunted across these induction coils at suitable points are four carbon microphones, or other telephone transmitters 8. The sets of bridge arms 4, 6, and 5, 7 are electrically connected by conductors 9, which in turn are connected by electrical conductors 10 with an adjustable primary winding 11, and to a make and break telegraph key 12. The secondary winding 13 of the transformer 11, is connected with two carbon microphones, or other telephone transmitters 14 in an electric circuit and also two spark gaps 15 in series in said circuit. The spark gaps 15 are shunted by variable condensers

16, telephone transmitters 17, and adjustable induction coils 18 in said electric circuit. The induction coils 18 form primary windings for an air core transformer having secondary coils 19 which are in series and are connected with a carbon or other telephone transmitter 20 and with the aerial conductor 21 and earth conductor 22.

The bridge arms are not balanced for either direct or alternating current, but arms 4 and 7 may be of a low resistance and 5 and 6 may be of a high resistance or vice versa so that the microphone transmitters 8 shunted across the bridge arms will vary the current in primary coil 11 of the transformer. The induced current generated in the secondary coil of the transformer is varied by the microphone transmitters 14 in series with the spark gaps 15, and the intermittent current discharge across the spark gaps 15 is varied by condensers 16, induction coils 18 and by microphone transmitters 17. The induction coils 19 are influenced by an induced current from the induction coils 18 and are connected with the earth and the aerial transmitting conductor 21.

Any two or all of these transmitters may be used simultaneously which will cause a material variation in the electrical waves emitted by the aerial conductor.

One or both of the spark gaps may be used and a close or loose coupling employed for the aerial conductor, or the earth conductor.

The telegraph key 12 is used for signaling purposes only and when in use the microphone transmitters are either cut out of circuit or shunted by a suitable switch.

Referring to the figure, bridge arms 4 and 7 may be made low, and arms 5, and 6 may be made high or vice versa, so that the microphone transmitters 8 shunted across the bridge arms will vary the current in primary coil 11 of the transformer. The induced current generated in the secondary coil of the transformer is varied by the microphone transmitters 14 in series with the spark gaps 15, and the intermittent current discharge across the spark gaps 15 is varied by condensers 16, induction coils 18 and by microphone transmitters 17. The induction coils 19 are influenced by an induced current from the induction coils 18 and are connected with the earth and the aerial transmitting conductor 21. Any two or all of these trans-

mitters may be used which will cause a material variation in the electrical waves emitted by the aerial conductor. This device will operate when all of these transmitters are connected in circuit.

One or both of the spark gaps may be used and a close or loose coupling employed for the aerial conductor, or the earth conductor.

10 Having described the invention, I claim:—

1. In a system for the transmission and reception of vocal or other sounds including articulate speech without the use of guiding wires, a transmitting system comprising a transmitting conductor, a Wheatstone bridge located in said conductor having a number of inductance coils, microphones shunted across said coils, and a step-up transformer having an adjustable primary winding con-

nected with the inductance coils of the 20 Wheatstone bridge.

2. In a system for the transmission and reception of vocal and other sounds including articulate speech without the use of guiding wires, a transmitting system comprising a transmitting conductor, a Wheatstone bridge located in said conductor having a number of inductance coils, microphones shunted across said coils, and a step-up transformer having its primary winding 25 30 connected with the inductance coils of the Wheatstone bridge.

In testimony whereof I affix my signature in presence of two witnesses.

FRANK P. HERRGUTH.
